ADVERTISING DISPLAY DEVICE

Clifford B. Graben, Minneapolis, Minn., assignor
to General Mills, Inc., Minneapolis, Minn., a
corporation of Delaware

Application March 9, 1936, Serial No. 67,851

7 Claims. (Cl. 40—21)

This invention relates to new and useful improvements in advertising display devices, and more particularly to such devices adapted to be supported directly upon an article on display, for the purpose of displaying advertising and other matter pertaining to the article.

An object of the invention is to provide an advertising display device of simple and inexpensive construction, comprising a body of sheet material having tabs or tongues formed thereon and projecting in opposite directions, and adapted to be bent around the body of an article to secure the display device thereto, the ends of said tabs or tongues being secured together by a suitable flexible element.

A further object is to provide a display device of the character disclosed, comprising a normally flat body of sheet material having a surface adapted to receive advertising matter pertaining to the article on display, and said body having oppositely disposed tabs or tongues adapted to embrace or partially surround the body of the article on display, and suitable apertures and slits being provided in the ends of said tabs, through which an elastic element may be threaded to secure the ends of the tabs in position around the body of the article, thereby to secure the display device to the article in an upright, conspicuous position.

Other objects of the invention will appear from the following description and accompanying drawing and will be pointed out in the annexed claims.

In the accompanying drawing there has been disclosed a structure designed to carry out the various objects of the invention, but it is to be understood that the invention is not confined to the exact features shown as various changes may be made within the scope of the claims which follow.

In the drawing:

Figure 1 is a front view of the display device showing the simple construction thereof;

Figure 2 is a rear view of the device, showing it attached to an article, such as a sack of flour; and

Figure 3 is an enlarged detail view, showing the apertures and slits provided at the ends of the tabs for receiving the securing element.

The novel advertising display device, herein disclosed, is shown comprising a body portion, generally indicated by the numeral 2, constructed of sheet material, such as cardboard or paper. The device is made from a single blank of sheet material, as clearly illustrated in Figure 1, and the

lower portion thereof is shown slotted along the lines 3 and 4 to provide oppositely projecting tabs or tongues 5 and 6. These tabs are adapted to embrace or partially encircle the body of the article upon which the device is to be supported, as clearly shown in Figure 2. In Figure 2, the display device is shown mounted on an ordinary bag of flour, indicated by the numeral 7.

The body 2 of the device preferably has a central depending portion 8, the opposite edges of which are provided with the oppositely projecting tabs 5 and 6, as clearly shown in Figure 1. The material is preferably scored, as indicated by the broken lines 9 and 10, to facilitate bending the tabs 5 and 6 around the body of the article 7. If desired, these score lines may be omitted, particularly, if the device is to be supported upon an article whose body is more or less circular in cross-section, for example, a bag of flour.

An important feature of the present invention resides in the means provided for securing the display device to the article or bag 7. As shown in Figure 1, the tabs 5 and 6 are provided with suitable apertures 11 and slits 12. The slits 12 extend from the apertures 11 to the outer ends 13 of the tabs, whereby the portion 13, lying between the slits 12—12, may be bent out of the medial plane of the tab, as clearly illustrated in Figure 3. The inner ends of the slits 12 are so connected to the apertures 11 as to form concave seats 10 as best illustrated in Fig. 3. In other words, the inner ends of the slits are connected to the apertures adjacent the side edges of the tabs 5 and 6, whereby portions of the apertures are nearer the ends of the tabs than the inner or adjacent ends of the slits.

To secure the device to the article or bag, the tabs 5 and 6 are fitted around the body of the bag, as shown in Figure 2, and the ends of the tabs are then connected together by a flexible element such as a rubber band 14. This band is threaded through the slits 12 at the ends of the tabs, and into the apertures 11, in the manner illustrated in Figure 3, whereby the band 14 will engage the concave seats 10, as clearly illustrated in Figure 2. Because of the slits 12 being connected to the outer portions of the apertures 11, the looped ends of the endless rubber element or band 14 cannot accidentally become detached or disconnected from the ends of the tabs, as will readily be understood, by reference to Figure 2. The connecting element 14 may, however, readily be disconnected from the ends of the tabs by simply bending the intermediate portions 13 outwardly, as shown in Figure 3, whereby the

slits 12 are opened to permit the element 14 to readily pass therethrough.

In the drawing, I have shown the display device, as used in connection with a bag of flour or similar article, but it is to be understood that it may be used in connection with various other commodities, without departing from the scope of the invention.

When the display device is used for displaying articles or products made from flour as shown, for example, in Figure 1, a pad of recipes, generally indicated by the numeral 15, may be fastened on the device, as shown in Figure 1, which is so constructed that the recipes may readily be torn from the pad, one at a time, by anyone who may be interested.

The device, as hereinbefore stated, is very simple and inexpensive in construction and may readily be manufactured in quantity production at a very low cost. The particular arrangement of the tabs 5 and 6 and the means provided at the ends thereof, for securing the device to the article, is such that the device may readily and quickly be attached to the article or bag 7, as shown in Figure 2, with the body 2 of the device supported in an upright, conspicuous position upon the article, whereby it presents a very neat and attractive appearance which is extremely pleasing to the eye.

I claim as my invention:

1. An advertising display device comprising a normally flat body of sheet material having a surface for displaying advertising matter, said body having a depending portion provided with oppositely projecting tabs adapted to be bent around the body of an article on display, said tabs having slits extending inwardly from the ends thereof and terminating at their inner ends in concave seats, and an elastic band having its

looped ends seated in said concave seats and connecting together the ends of the tabs, thereby to secure the device to the article in a conspicuous position, said slits permitting the looped ends of the elastic band to be inserted into said seats.

2. An advertising display device comprising a normally flat body having a surface for displaying advertising matter, said body having a central depending portion provided with oppositely projecting tabs or tongues having apertures therein adjacent their outer ends, said tabs also having slits extending from the portion of said apertures nearest to the side edges of the tabs, thereby to provide a seat in each aperture, and said slits being open at their outer ends whereby the looped end of an elastic band may be passed therethrough into said seats, and whereby said elastic band will cooperate with said tabs to secure the device in an upright position on the body of an article on display.

3. An advertising display device comprising a flat body of sheet material having a surface for displaying advertising matter, said body having a depending portion provided with oppositely projecting tabs or tongues having apertures therein adjacent their outer ends, and said tabs having slits therein extending from the portions of said apertures nearest to the outer edges of the tabs, thereby to provide a concave seat in each aper-

ture, and whereby the central portions of the ends of the tabs may be bent outwardly to permit a securing element to be threaded through said slits into said concave seats, thereby to hold the tabs in embracing engagement with the body of an article to retain the device in position on the article.

4. In combination with a filled flexible container or bag, an advertising display device comprising a flat body adapted to be positioned against one side of the bag, said body having a depending portion fitting against the lower portion of the bag body and provided with oppositely projecting tabs or tongues adapted to embrace the bag body, said tabs having spaced apertures adjacent their outer ends, and slits extending from said apertures to the ends of the tabs, said slits being connected to the portions of said apertures adjacent the outer edges of the tabs, whereby a portion of each aperture is nearer the end of its respective tab, than the point of connection of the slit therewith, and an endless elastic band having its looped ends inserted through said slits into said apertures and cooperating with said tabs to secure the device to the bag in an upright position.

5. An advertising display device comprising a normally flat body of sheet material having a surface for displaying advertising matter, said body having slits extending inwardly from the opposite sides thereof, and terminating at their inner ends in suitable apertures offset from their respective slits in a direction towards one another to provide concaved seats, said slits being so arranged that the looped ends of an elastic band may be passed therethrough into said seats to secure the band to said body, and whereby the elastic band may detachably support the device in proper position upon an article.

6. An advertising display device comprising a normally flat body of sheet material having a surface for displaying advertising matter, said body having a pair of spaced apertures therein adjacent each of its side edges, and each aperture having one end of a slit connected thereto at the point thereof most remote from its complementary aperture, and whereby said apertures provide inwardly facing concaved seats at the inner ends of said slits adapted to receive the looped ends of an elastic band which band may be fitted around an article to support the device in position thereon.

7. In a device of the class described, a body portion of sheet material having a surface for displaying advertising matter, said body having a pair of spaced apertures therein adjacent a side edge thereof, and each aperture having one end of a slit connected thereto at the point thereof most remote from the other aperture, whereby inwardly facing concaved seats are provided at the inner ends of said slits, and an elastic band having one end suitably connected to said body portion and adapted to be passed around the body of an article and have its opposite end detachably received in said concaved seats, thereby to support the device in position on the article.

CLIFFORD B. GRABEN.
